UNITED STATES PATENT OFFICE.

HERMAN RAU, OF HAMILTON BEACH, NEW YORK, ASSIGNOR TO DOEHLER DIE-CASTING CO., A CORPORATION OF NEW YORK.

DIE FOR DIE CASTING.

Application filed March 7, 1923. Serial No. 623,386.

To all whom it may concern:

Be it known that I, HERMAN RAU, a citizen of the United States, residing at Hamilton Beach, L. I., in the county of Queens 5 and State of New York, have invented certain new and useful Improvements in Dies for Die Casting, of which the following is a full, clear, and exact description.

While embodiments of my invention may 10 have a general application to the art of die-casting under pressure, they have especial utility in connection with the method of making molds for finished castings which forms the subject matter of the patent to 15 John Kralund, Number 1,335,509, granted on March 30th, 1920, and to which my prior patent of November 16, 1920, Number 1,359,196, also relates. That method contemplates the formation of so-called match 20 plates from which molds for the final casting are made of plastic composition. The match plates are composed of a plurality of units which are assembled in a complete match plate, and have base portions with 25 smooth upper surfaces which produce the parting surfaces of the molds formed thereon, and integral raised portions constituting the patterns for the mold cavities. These match plate units are die-cast from a 30 suitable alloy, and it is in the die-casting of these units that my invention has a particular advantage. My invention will therefore be described with reference to the match plates to be used in this method but it will 35 be understood that the invention contemplates embodiment in dies for any die-casting so far as it may be practically applied thereto, and that the invention is not limited except as hereinafter pointed out in the 40 claims.

The match plates are formed from white metal models which are individually cast in a metal die having a proper mold cavity, and which are then trimmed down and assembled on an iron plate. These unit models 45 have a rectangular base of proper proportions to accommodate the particular pattern raised thereon, and are generally about a quarter of an inch thick. The dies or impression blocks in which these have been 50 heretofore cast have, therefore, a rectangular cavity in the bottom of which is a depression for forming the pattern and also the necessary runs and branches.

55 By my invention I am able materially to

simplify as well as reduce the cost of these dies, and also to reduce the size of the permanent impression block which is preserved for future use. In accordance with my invention I provide what may be termed an 60 adjustable die, which makes it possible to use removable impression blocks and thus facilitate changing from one design of casting to another.

The die itself is preferably permanently 65 attached to a standard die base or ejector box, and consists of a base plate having side pieces on its outer face which enclose a space for an impression block and which are adjustable to accommodate impression 70 blocks of various size. For making match plates the adjustable die will usually have four side pieces, one of which will be stationary and have the gate and sprue cutter openings, while the other three will be adjustable relative thereto. A suitable cover plate will complete the die. In this way the 75 side pieces serve as the outside boundaries for the mold cavity, while the thickness of the base of the match plate units is determined by the difference in height between the side pieces and the impression block enclosed by them.

I shall now describe the illustrated embodiment of my invention and shall there- 80 after point out my invention in claims.

Fig. 1 is a plan of one embodiment of my invention with the cover plate removed.

Fig. 2 is a sectional elevation of the complete die on line 2-2 of Figure 1.

Fig. 3 is a sectional elevation of the same on the irregular line 3-3 of Figure 1.

Fig. 4 is a plan of an impression block which may be used with the die.

Fig. 5 is a central longitudinal sectional 90 elevation of the same.

Fig. 6 is a plan of the match plate unit produced by the die and illustrated impres- 95 sion block.

Fig. 7 is a side elevation of the same.

The base plate 1 is provided in each corner with a tap hole 2 for fastening to the four corner legs of the die base or ejector box 3. The ejector plate 4 carries the ejector pins 5, the number and arrangement 100 of which depend upon the casting. In practice, the plate 1 could be provided with a number of holes in its central area which will accommodate any number or arrangement of ejector pins. The plate 1 is also provided 105

110

toward one edge with a row of elongated openings or slots 6 (shown three in number), and with an opening for the sprue cutter 7. At right angles to the line of the row of 5 slots 6 is a groove 7^a in the outer face of the plate which is disposed toward and parallel to one side of the plate.

On the outer face of the plate 1 are disposed four oblong blocks 8, 9, 10 and 11 10 which are arranged to enclose a rectangular space in the center of the plate 1 for an impression block. Of these blocks, the block 8 is stationary and the other three blocks are adjustable to vary the size of the enclosed 15 space. These blocks are all of the same height and are covered by a cover plate 12 to complete the die.

The stationary block 8 is secured in any suitable way to the face of the plate 1 substantially 20 in one corner thereof, and has an opening 13 for the sprue cutter 7 in line with the sprue cutter opening through the plate 1. In the outer face of this block 8 is a suitable recess 14 which serves as an inlet or gate for the molten metal. This recess is shown as flaring in both directions 25 from the sprue cutter opening 13. Two dowel pins 15 on this block serve to locate the top or cover plate 12, which cover plate 30 has a gate inlet 16 which is aligned with the sprue cutter opening when the plate 12 is in place.

The block 9 has on its under face a longitudinal tongue which fits in the groove 7^a, 35 and the inside longitudinal face of the block 9 abuts against the inner end of the stationary block 8. To retain the block 9 in place and at the same time allow it to be adjusted longitudinally of the groove 7^a, 40 square headed bolts 17 extend through the plate 1 in the groove 7^a with the headed end projecting above the face of the plate and engaging in a longitudinal T-slot 18 in 45 the under side of the block 9. It is evident that the release of the nuts of these bolts 17 permits of the adjustment of the block 9, and that the block is locked in any adjusted position by tightening up the nuts.

The block 10, which is disposed parallel 50 to the stationary block 8, is mounted for adjustment both transversely and longitudinally. In the construction shown, it is provided in its under face with a longitudinal T-slot 19 in which engage the head ends 55 of square headed bolts 20 passing through the elongated openings or slots 6 in the base plate 1.

The block 11 is provided in its under face with two transverse T-slots 21 in which 60 engage two square headed bolts 22 which pass through the plate 1 and are disposed in a line parallel to the slot 7^a.

The adjustment of all three of the adjustable blocks is permitted merely by letting up on the nuts on the guide bolts for

the respective blocks. The inner end of the block 11 abuts against the inner face of the stationary block 8 throughout its adjustment. Any size opening to receive the impression block in the center of the die 70 may be obtained within the range of the movable members. To vary the length of this space the block 11 is adjusted in or out and the block 10 is longitudinally adjusted to keep its inner end in abutment with the 75 inner longitudinal face of the block 11. To vary the width of the enclosed space the block 10 is adjusted transversely toward or from the stationary block 8, which is effected by moving the bolts 20 in the slots 6. 80 The block 9 is longitudinally adjusted to compensate for any lateral adjustment of the block 10.

To construct a die for any desired casting, it is only necessary in accordance with 85 this invention, to make a die block or impression block of suitable size having the desired impression cut therein, and to assemble this impression block with the adjustable blocks 9, 10 and 11. A sample impression block is illustrated in Figures 4 and 5, and is indicated by dotted lines in position in Figure 2, being secured against the base plate 1 by screws, as represented. The match plate unit cast from this die is illustrated in Figures 6 and 7.

By this invention the necessity for building a special ejector box for each casting is avoided and the amount of special steel for producing the impression cavity is materially reduced.

It is obvious that various modifications may be made in the construction shown in the drawings and above, particularly described, within the principle and scope of 105 my invention.

I claim:

1. An adjustable die for pressure casting comprising, in combination with an ejector member, a bottom plate through which the ejector member passes, and side pieces on the outer face of the plate arranged to enclose an impression block space and adjustable to vary the dimensions of the enclosed space.

2. An adjustable die for pressure casting comprising, in combination with an ejector member, a bottom plate through which the ejector member passes, and side pieces on the outer face of the plate arranged to enclose an impression block space, one of the side 120 pieces being stationary and having a gate recess in its outer face leading to the enclosed space and certain of the other side pieces being adjustable to vary the dimensions of the enclosed space.

3. An adjustable die for pressure casting comprising, in combination with an ejector member, a bottom plate through which the ejector member passes, side pieces on the outer face of the plate arranged to enclose 130

an impression block space one of the side pieces being stationary and having a gate recess in its outer face leading to the enclosed space and certain of the other side pieces being adjustable to vary the dimensions of the enclosed space, and a cover plate on the side pieces having a gate opening communicating with the said gate recess in the stationary side piece.

10 4. An adjustable die for pressure casting comprising, in combination with an ejector member, a bottom plate through which the ejector member passes having an opening therethrough for a sprue cutter, a stationary block secured on the outer face of the plate and having a hole therethrough registering with the said sprue cutter opening and a gate recess on its outer face communicating with the said hole, and three complementary blocks cooperating with the said stationary block to enclose a space on the bottom plate for an impression block including the opening for the ejector member, one of said complementary blocks being longitudinally adjustable and another being laterally adjustable to vary the dimensions of the enclosed space.

5. An adjustable die for pressure casting comprising, in combination with an ejector member, a bottom plate through which the ejector member passes having an opening therethrough for a sprue cutter, a stationary block secured on the outer face of the plate and having a hole therethrough registering with the said sprue cutter opening and a gate recess on its outer face communicating with the said hole, and three complementary blocks cooperating with the said stationary block to enclose a rectangular space on the bottom plate for an impression block including the opening for the ejector member, the block parallel to the stationary block being adjustable both longitudinally and vertically, and one of the other two blocks being adjustable laterally and the other being adjustable longitudinally, whereby the dimensions of the enclosed space may be altered.

6. An adjustable die for pressure casting comprising in combination with an ejector box, a plate secured to the ejector box carrying a plurality of protruding headed bolts, a stationary block secured to the face of the

plate, and a plurality of complementary blocks cooperating with the stationary block to enclose a space for an impression block 55 and having T-slots therein engaging over the headed bolts and adjustable therein to vary the size of the enclosed space.

7. An adjustable die for pressure casting comprising, in combination with an ejector 60 box, a plate secured to the ejector box having a groove across its outer face and a plurality of slots arranged in a line transverse to the groove, a plurality of protruding headed bolts in the groove, a headed bolt in each slot, and a 65 row of protruding headed bolts parallel to the groove, a block having a longitudinal tongue engaging in the groove and a longitudinal T-slot engaging over the bolts in the groove, a second block having a longitudinal T-slot 70 engaging over the bolts in the slots, a third block having transverse T-slots engaging over the said row of bolts, and a stationary block secured to the face of the plate and cooperating with the other three blocks to 75 enclose a rectangular space for an impression block.

8. An adjustable die for pressure casting comprising, in combination with an ejector box, a plate secured to the ejector box having a groove across its outer face and a plurality of slots arranged in a line transverse to the groove, a plurality of protruding headed bolts in the groove, a headed bolt in each slot, and a row of protruding headed bolts parallel to the groove, a block having a 80 longitudinal tongue engaging in the groove and a longitudinal T-slot engaging over the bolts in the groove, a second block having a longitudinal T-slot 85 engaging over the bolts in the slots, a third block having transverse T-slots engaging over the said row of bolts, a stationary block secured to the face of the plate and cooperating with the other three blocks to enclose a rectangular space for an 90 impression block, the stationary block having a gate recess leading to the enclosed space, and a cover plate on the blocks having a gate opening communicating with the gate recess in the stationary block. 95

In witness whereof, I hereunto subscribe my signature.

HERMAN RAU.
